CLAIM

The ornamental design for a hydration cart as shown and described.

DESCRIPTION

FIG. 1 is a perspective view of a hydration cart showing the new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a perspective view of the hydration cart of FIG. 1 shown in a secondary configuration;

FIG. 9 is a front view thereof;

FIG. 10 is a rear view thereof;

FIG. 11 is a right-side view thereof;

FIG. 12 is a left-side view thereof;

FIG. 13 is a top view thereof;

FIG. 14 is a bottom view thereof; and,

FIG. 15 is a perspective view of the hydration cart of FIG. 8.

The even-length broken lines in the figures represent portions of the hydration cart that form no part of the claimed design. The broken lines in FIG. 15 are to show environment and form no part of the claimed design.

1 Claim, 15 Drawing Sheets
